DESIGN FOR A PLIER

Alfred H. Miller, Philadelphia, Pa., assignor to
Utica Drop Forge & Tool Corporation, a cor-
poration of New York

Application January 5, 1945, Serial No. 117,290

Term of patent 14 years

(Cl. D54—13)

To all whom it may concern:

Be it known that I, Alfred H. Miller, a citizen of the United States, residing in the city of Philadelphia, county of Philadelphia, and State of Pennsylvania, have invented a new, original, and ornamental Design for Pliers, of which the following is a specification, reference being had to the accompanying drawing, forming a part thereof.

Figure 1 is a side view of a plier showing my new design; and

Figure 2 is a bottom view thereof.

I claim:

The ornamental design for a plier, substantial-
ly as shown.

ALFRED H. MILLER.
